ATTORNEY

UNITED STATES PATENT OFFICE.

JOHN J. TONKIN, OF OSWEGO, NEW YORK.

STEAM-BOILER.

SPECIFICATION forming part of Letters Patent No. 678,530, dated July 16, 1901.

Application filed November 12, 1900. Serial No. 36,172. (No model.)

To all whom it may concern:

Be it known that I, JOHN J. TONKIN, a citizen of the United States, and a resident of Oswego, in the county of Oswego, in the State 5 of New York, have invented new and useful Improvements in Steam-Boilers, of which the following, taken in connection with the accompanying drawings, is a full, clear, and exact description.

10 In the accompanying drawings is illustrated a steam-boiler embodying my present invention, which is a specific improvement of the boiler shown and described in my prior application for Letters Patent, Serial No. 26,701, 15 filed August 13, 1900, and in said drawings—

Figure 1 is a vertical transverse section, and Fig. 2 is a horizontal transverse section on line X X in Fig. 1.

In said prior application the construction 20 of the boiler is such as to make it particularly desirable for furnishing the propelling power for locomobiles.

As set forth in the application referred to, the essential elements of the boiler are two 25 upright shells, superposed one upon the other and constituting, respectively, the steam-chamber and water-chamber, and a flue-sheet or diaphragm secured to said shells at their junction. In that case the shells are flanged 30 outward at their junction and the flue-sheet or diaphragm is seated with its margin between said flanges and riveted thereto.

The present invention resides in an improved manner of uniting said elements, the 35 object being to increase the stiffness and strength of the boiler and also to lessen the liability of leakage at the union of said parts.

It will be clearly understood, without necessarily referring to the drawings of the prior 40 application, that by seating the flue-sheet or diaphragm between the flanges of the shells, as described, a joint is created between the flue-sheet and upper shell and also between said flue-sheet and lower flange. Therefore 45 there are two joints to be calked, at which there is a possibility of leakage, to which all boilers are liable, while in my present construction there is but one joint produced at the junction of said parts, as clearly seen in 50 Fig. 1. By flanging the two shells outward, as stated, a projection or ledge is produced on the exterior of the boiler, which projec-

tion has been utilized in some cases to support the boiler on the frame of the locomobile. It has been found, however, in other cases 55 that owing to the peculiar construction of certain vehicle-frames said projection or ledge is not useful for the purpose and, in fact, is objectionable. Therefore another object of the present invention is to dispense with said 60 projection and unite the two shells and flue-sheet or diaphragm in such a manner as to produce a more rigid and stronger construction and at the same time improve the appearance of the boiler. 65

Referring to the annexed drawings, A represents the lower shell, A' the upper shell, B the diaphragm, which constitutes a flue-sheet, and a a are the usual flues or tubes, which are disposed vertically. 70

The shell A' is superposed upon the lower shell A and constitutes the steam-chamber, the lower shell constituting the water-chamber. Said shells are joined telescopic and are firmly secured together by means of rivets b b. 75

The flue-sheet or diaphragm B is preferably formed integral with the top of the lower shell and serves to guard against foaming of the boiler and to prevent the water from entering into the steam-space. However, it will 80 be seen that said flue-sheet may be formed of a separate plate and riveted to the shell in any suitable manner. Said flue-sheet or diaphragm B is provided with a plurality of small perforations c c, which allow the steam 85 to enter into the chamber A'.

The base of the lower shell A is formed with an outwardly-projecting perforated flange d, to which is secured a flue-sheet e by means of rivets f f. 90

The top of the upper shell A' is provided with a flue-sheet g, similar to the flue-sheet e, and said flue-sheets coincide with the intermediate flue-sheet or diaphragm B.

The flues or tubes a a extend through the 95 three flue-sheets and are firmly secured at their ends to the top and bottom flue-sheets.

h represents the usual steam-pipe, which preferably extends from the center of the flue-sheet g, and i is the usual water-pipe, 100 which communicates with the water-chamber A, preferably through the center of the flue-sheet e.

C denotes a suitable case, which contains

the usual gasoline or other burner. (Not necessary to be shown.) Said case may be attached to the boiler in any suitable manner. In this case I have shown an angle-iron *n*, secured to the shell *A* by means of rivets *b' b'* and detachably secured to a flange *c'* formed at the top of the case by means of bolts *d' d'*.

5 The products of combustion from the burner pass through the tubes *a a* and effectually 10 heat the water in the chamber *A*, and the generated steam passes through the dia- phragm *B* in a dry state to the steam-cham- ber *A'*.

What I claim is—

- 15 1. A steam-boiler composed of upright shells superposed one upon the other and united by telescopic joint, the bottom and top of the boiler consisting of flue-sheets, a coinciding flue-sheet extending across the interior 20 of the boiler at the water-level thereof and provided with steam-passages, and flues ex- tending through said three flue-sheets and fastened to the bottom and top flue-sheets as set forth.
- 25 2. A steam-boiler composed of an upright water-chamber having its top and bottom plates perforated, said top plate being pro- vided with steam-passages, a steam-chamber joined telescopic to the exterior of the upper

portion of the water-chamber and having its 30 top plate perforated, and flues extending through the perforations of said three plates as set forth.

3. A steam-boiler composed of upright shells superposed one upon the other and 35 joined telescopic, a flue-sheet extending across the bottom of the lower shell, a coinciding flue-sheet extending across the top of the upper shell, and a similar flue-sheet extending across the two shells at the junction thereof, 40 and provided with steam-passages, and flues extending through said three flue-sheets as set forth.

4. A steam-boiler composed of upright shells superposed one upon the other, the 45 lower shell extending near the water-line of the boiler and flanged at its base and formed at its top with a flue-sheet provided with steam-passages, a flue-sheet fastened to the flanged base of said shell, the upper shell 50 joined telescopic to the lower shell and formed with a flue-sheet at its top, and flues extending through said three flue-sheets as set forth and shown.

JOHN J. TONKIN. [L. S.]
